United States Patent Office

Des. 210,470

Patented Mar. 12, 1968

210,470

GAME BOARD OR THE LIKE

James E. Ison, 719 Bromley Road,
Ludlow, Ky. 41016

Filed May 23, 1967, Ser. No. 7,232

Term of patent 7 years

(Cl. D34—5)

Fig. 1

Fig. 2

FIG. 1 is a top plan view showing my new design for a game board or the like.

FIG. 2 is a side elevational view of the game board shown in FIG. 1.

Conventional numerals are shown in broken lines.

I claim:

The ornamental design for a game board or the like, as shown and described.
